(57) CLAIM

The ornamental design for a snow globe cup, as shown and described.

DESCRIPTION

FIG. 1 is a front view of a Snow Globe Cup showing my new design;

FIG. 2 is a side view thereof;

FIG. 3 is a cross sectional view showing a section taken along line 3-3 of FIG. 5;

FIG. 4 is a bottom plan view thereof;

FIG. 5 is a top plan view thereof;

The broken lines in the drawings depict portions of the Snow Globe Cup that form no part of the claimed design.
